FUSE

Filed Sept. 20, 1926

FIG. - 1 -

UNITED STATES PATENT OFFICE

DAVID L. WOODBERRY, OF BALTIMORE, MARYLAND, ASSIGNOR TO SECRETARY OF WAR
OF THE UNITED STATES OF AMERICA

FUSE

Application filed September 20, 1926. Serial No. 136,662.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 The subject of this invention is a fuse especially designed as a nose fuse for bombs but not restricted thereto.

In carrying out bombing operations the 10 nature and character of the target together with the object sought controls the type of fuse to be employed. Because of the different actions which must be provided for, it is obviously of considerable convenience and 15 advantage in fabrication and distribution to combine in a single fuse elements which without adjustment will meet varying conditions.

According to the present invention the 20 fuse is provided with a plurality of powder trains adapted to produce instantaneous and delay action while the functioning of the igniting elements is governed by the nature and degree of impact. On light impact at 25 low velocity the delay train will control while on heavy impact the fuse will be instantaneously set off.

With these and other objects in view which will appear as the description proceeds, my 30 invention resides in the novel arrangement and combination of parts and in the details of construction hereinafter described and claimed, it being understood that changes in the precise embodiment of the invention 35 herein disclosed may be made within the scope of what is claimed without departing from the spirit of the invention.

A practical embodiment of the invention is illustrated in the accompanying drawing 40 wherein:

Fig. 1 is a longitudinal sectional view of a fuse embodying the principles of the invention and shown in unarmed position;

Fig. 2 is a view in elevation and partly in 45 section at right angles to Fig. 1; and

Fig. 3 is a sectional view on the line 3—3 of Fig. 1.

Referring to the drawing by numerals of reference:

50 The fuse comprises a cylindrical casing or

body 5 in which is a block 6 held in place by a booster casing 7 carrying a booster charge 8. In the outer portion of the body is a fuse head 9 spaced from the block 6 and detachably secured as by a threaded connection 10 which is capable of being stripped when the head is driven in. The fuse head is auxiliarily supported by a resistance ring 11 interposed between the flange 9a of the fuse head and the rim of the body and adapted to be crushed on heavy impact while the threaded connection is being broken. The fuse head is provided in its under face and off center with a fixed firing pin 12 positioned directly over a primer 13 in the block which communicates through the passage 14 with a relay charge 15 positioned axially of the fuse.

The fuse head is centrally bored to receive the stem 16 of a pressure plate 17 which is held, when armed and during arming, in spaced relation with respect to the block 6 by means of a spring 18 which is of sufficient strength to overcome the air pressure encountered during flight. The stem 16 is provided with a firing pin 19 positioned directly above the delay train 20 axially of the block 6, and the pin is normally held from contact with the primer of said train when the fuse is unarmed by a vane unit 21 which when connected by a threaded spindle 22 to the pressure plate, is in or near engagement with the flange 9a of the fuse head whereby its further inward movement is prevented. The pressure plate 17 is held against rotation and against movement away from the fuse head during unthreading of the vane unit by means of a pin 23 carried by the firing pin 19 and extending into a longitudinal slot 24 in the fuse head.

Mounted for slidable movement in a passage 6a in the block perpendicularly to the axis of the fuse is a cylindrical bolt 25 containing a detonating charge 26. The bolt is normally held in unarmed position by means of a rod 27 passing through the fuse head and pressure plate and engaged by the spindle 22 whereby it is moved therewith from engagement with the bolt. When released, the bolt is urged to armed position by one or

more springs 28 where it is held by a plunger 29.

The main unit 21 is normally held against rotation in the customary manner by means of a pin 30 passing through ears 31 and 32 respectively on the vane unit and fuse head and replaceable by the release wire of the standard launching mechanism carried by an airplane.

10 Upon light impact when the bomb strikes a yielding surface at a low velocity, the pressure plate will be forced inwardly until the firing pin carried thereby sets off the delay train 20 which communicates ignition to the 15 relay charge 15. If a heavy impact is encountered the resistance ring 11 is crushed and the fuse head is driven in stripping the threads 10. Both the firing pins 12 and 19 will function under these conditions but the 20 primer 13 will communicate ignition instantaneously to the relay charge.

In case a light impact is first obtained and a heavy impact occurs before the expiration of the set delay instantaneous action will 25 result.

I claim:

1. A nose fuse for bombs including a body, a delay and an instantaneous powder train in the body, the delay train arranged axially of the body, a fuse head including a fixed firing pin positioned above the instantaneous train and having a threaded connection with the body adapted to be stripped on heavy impact, a resistance ring interposed between the head and body and adapted to be crushed on heavy impact, a pressure plate having a stem disposed in the fuse head and mounted for longitudinal movement with respect thereto, a firing pin on the stem, and a vane assembly normally holding the plate in unarmed position and unthreadable therefrom during flight to arm the plate.

2. A nose fuse for bombs including a body, a delay and an instantaneous powder train

in the body, a fuse head including a fixed firing pin positioned above the instantaneous train and having a threaded connection with the body adapted to be stripped on heavy impact, a pressure plate having a stem disposed in the fuse head and mounted for longitudinal movement with respect thereto, a firing pin on the stem and a vane assembly normally holding the plate in unarmed position and unthreadable therefrom during flight to arm the plate.

3. A nose fuse for bombs including a body, a delay and an instantaneous powder train in the body, a fuse head including a fixed firing pin positioned above the instantaneous train, said head arranged for longitudinal movement on heavy impact only, a firing pin member carried by the fuse head and arranged for longitudinal movement on light impact, a vane assembly normally holding the light impact firing pin member in unarmed position and unthreadable therefrom during flight to arm said member.

4. A fuse including a body, a fuse head provided with a firing pin and having a connection with the body adapted to be stripped on heavy impact, a resistance ring interposed between the head and body and adapted to be crushed on heavy impact and a light impact firing pin member carried by the fuse.

5. A fuse including a body, an axial delay train in the body, an instantaneous train disposed radially with respect to said axial train and means movable in the same direction for igniting said trains respectively on light and heavy impact.

6. A fuse, including a body, a fuse head frangibly connected to the body and adapted to be disconnected therefrom on heavy impact and a light impact member overlying the fuse head and having a portion extending therethrough.

DAVID L. WOODBERRY.
